UNITED STATES PATENT OFFICE.

ANDREW G. STEINBRENNER, OF ST. LOUIS, MISSOURI.

GRAIN-CAR DOOR.

SPECIFICATION forming part of Letters Patent No. 746,400, dated December 8, 1903.

Application filed September 12, 1903. Serial No. 173,013. (No model.)

To all whom it may concern:

Be it known that I, ANDREW G. STEINBRENNER, a citizen of the United States, residing in the city of St. Louis, in the State of Missouri, have invented certain new and useful Improvements in Grain-Car Doors, of which the following is a full, clear, and exact description, reference being had to the accompanying drawings, forming part of this specification.

My invention relates to an improvement in doors for grain-cars, and has for its object the production of a door that may be the most easily swung upwardly to the roof of the car in which it is positioned when the doorway is open and lowered from its elevated position to again close the doorway.

The invention consists in features of novelty hereinafter fully described, and pointed out in the claims.

Figure I is a front elevation of my grain-car door. Fig. II is a vertical section through the door. Fig. III is a rear or inside elevation of the door. Fig. IV is an edge view of the door, partly broken out. Fig. V is a section of one corner of the door shown connected to one of the upper hanger-brackets from which the door-supporting rods are suspended. Fig. VI is a horizontal section taken on line VI VI, Fig. III. Fig. VII is a horizontal section taken on line VII VII, Fig. IV. Fig. VIII is a perspective view of one of the corner-hooks carried by the door. Fig. IX is a horizontal section taken through one of the securing-bolts of the door.

1 designates the posts of a grain-car doorway, and 2 the roof of the car.

3 designates the car-door, which is positioned against the inside faces of the posts 1, and 4 is an apron surmounting the door 3 and connected thereto by hinges 5 to provide for its being folded downwardly in the direction indicated by dotted lines in Fig. II, so that it will lie against the inside face of the door when the car is empty and the door is to be elevated away from the doorway it controls. The apron is when surmounting the door upheld by catch-hooks 6, that are pivoted to the door-posts 1.

50 7 is a swinging catch mounted on the door

3 and adapted to be swung into engagement with the apron 4 when said apron is folded thereto.

8 designates bolt-boxes fixed to the door 3 and containing slide-bolts 9, by which said door may be held to the door-posts. When it is in position to close the doorway, these slide-bolts are adapted to enter keepers 10, (see Fig. IX,) fitted to the door-posts in alignment with the locations of the slide-bolts. 60

In the door 3 are discharge-apertures 11, which are controlled by shutters 12, that ride in guides 13. These openings and shutters do not form any part of my present improvement, and no invention is herein claimed for 65 them.

14 designates strips secured to the ends of the door 3, near the top thereof, and provided with pivot-studs 15.

16 designates hanger-brackets secured to 70 the upper ends of the door-posts 1 and bearing-studs 17 projecting from their inner side faces. Within these hanger-brackets are transverse pivots 18. 19 designates swinging rods having elongated eyes 20 at their 75 upper ends that are fitted to the pivots 18 of the hanger-brackets 16 and having at their lower ends eyes 21, that are fitted to the pivot-studs 15 of the strips 14.

22 designates hooks secured to the door 3 80 at its lower corners, the said hooks being preferably set into the door, as seen in Fig. IV.

In the practical use of my door it is readily disposed of by swinging it to the roof of the car after the car has been partially emptied 85 and upheld in such position by a suitable supporting-catch 23. (See Fig. II.) When the door is to be swung into elevated position, as mentioned, the apron 4 is first released from its supporting-catches 6 and 90 folded downwardly onto the door. The entire door is then swung upwardly, as shown by the short dotted lines, Fig. II, it being pivotally supported and moved on the pivot-stems 15, which are mounted in the lower 95 eyes 21 of the swinging rods 19. When the movement of the door, as stated, has been accomplished, the door is in inverted position and occupies the upper part of the doorway only. On the door being inverted the cor- 100

ner-hooks 22 at the bottom of the door, which are at such time elevated to the hanger-brackets 16, are slipped onto the studs 17 of said hanger-brackets, so that the door will be 5 swingingly supported in its inverted position. The top of the door, which is then lowermost, is next grasped and is swung on the studs 17 and elevated to the roof of the car, as seen by dotted lines, Fig. II, where the door is up- 10 held by the supporting-catch 23. As the door is raised to the roof of the car the swing- rods 19 travel therewith owing to their connection to the strip 14 and its pivot-studs, and said rods therefore remain connected to 15 the door ready to serve as supports for the door when it is next lowered for service as before.

I claim as my invention—

1. In a grain-car door, the combination with 20 the door and door-posts, of hangers fixed to said posts, swing-rods forming connection between said hangers and said door, and means carried by said door to engage with said hangers when the door is inverted and

its lower end is raised to said hangers, substantially as set forth. 25

2. In a grain-car door, the combination with a door and door-posts, of hangers secured to said posts, studs projecting from said hangers, swing-rods forming connection between said 30 hangers and said door, and hooks located at the bottom of said door for engagement with said hanger-studs when the door is in inverted position, substantially as set forth.

3. In a grain-car door, the combination with a door and door-posts, of hangers secured to said posts, studs projecting from said hangers, swing-rods having their upper ends loosely connected to said hangers, studs projecting from said door and receiving the loose connection of said swing-rods, and hooks carried by said door at its lower end to engage said hanger-studs when the door is in inverted position, substantially as set forth. 35 40

ANDREW G. STEINBRENNER.

In presence of—

E. S. KNIGHT,

NELLIE V. ALEXANDER.
